6 Claims. (Cl. 62—126)

1

This invention relates to refrigerators of the absorption type, and more particularly to small low temperature chambers within the main refrigerators, said small chambers being used principally for the making of ice-blocks and such like purposes where the descent in temperature should be as rapid as possible, and the temperature is normally considerably lower than that of the refrigerator proper. Such low temperature chambers have been a feature of refrigerators for many years and the difference in conductivity of metals has been the means whereby these small chambers have been rapidly lowered in temperature and maintained at low temperature while the refrigerator proper has been normally maintained at a higher temperature sufficient for the storage of foodstuffs and the like. Usually an iron evaporating pipe enclosed in a box is provided with a door and made up of metal having a higher heat conductive capacity, the shelving within the box being also of a metal having a higher conductive capacity, such as copper or aluminium. The ice trays are placed upon the shelves within the said box.

The object of this invention is to provide means whereby a low temperature chamber may be manufactured with a minimum number of standardised sections, which may be rapidly assembled and built into the refrigerator proper, providing a chamber having the qualities required.

The nature of the invention will be fully understood from the following description taken in connection with the accompanying drawings wherein:

Figures 1 and 2 are respectively front and side elevations of a low temperature chamber;

Figures 3, 4 and 5 are detail views of the evaporator pipe with parts of the assembly in position;

Figure 6 is an enlarged vertical sectional detail view of one shelf and associated parts;

Figure 7 is an enlarged vertical sectional detail view of a modified half-sleeve for supporting a shelf;

Figures 8 and 9 are respectively plan and side elevation of a liner;

Figures 10, 11 and 12 are respectively plan, front elevation and side elevation of a shelf;

Figures 13 and 14 are front and side elevations of a cover plate.

Figure 15 is a sectional view of a modified construction.

Referring to the drawings in which like numerals denote the same parts in the different figures, 1 denotes the sheet metal sides and back of an outer casing, said sides being provided with

2

front and top flanges 1a and 1b. 2 denotes the half-sleeves provided with flanges 3 by which the said half-sleeves 2 are spot-welded, soldered, sweated or riveted to the sides 1. The evaporator pipe is designated by reference character 4. Longitudinal channelled fins 5 are formed upon half-sleeves 2. In Figure 6 the half-sleeves 2, flanges 3 and fins 5 are an integral casting or extrusion, whereas in Figure 7 the same parts are formed by pressing sheet metal. Reference numeral 6 denotes a shelf (see Figures 10, 11 and 12) which is rectangular with its end 6a bent up at right angles, and provided with slots 6b and with chamfered corners 6c. Liners 7 (see Figures 8 and 9) are also provided. 8 denotes the front cover plates (see Figures 13 and 14). A top plate 9 is provided with turned side edge 9a adapted to snugly enclose the flanges 1b of sides 1. A door 10 is mounted on the face plate 10a. 11 denotes the ammonia pipe, and 12 the gas heat exchanger.

According to the invention the evaporator pipe 4 is made up of a series of parallel U-shaped sections or turns lying one above the other connected by curved junctions at their ends, except one upper and one lower end which ends are connected to the ammonia pipes. A liquid refrigerant, for example ammonia, is passed through the pipe 4 as is usual practice. The junctions 25 are made by curving downwardly an end of each section, so that it may be welded or otherwise secured to the adjacent end of a section immediately beneath it. Obviously the junctions of the sections are alternatively disposed at opposite 30 ends of the section as they descend so that there will be a continuous passage for the gas, and so that the inlet end of the uppermost section will be slightly higher than its other end, and so that as the sections descend that end connected to the curved junction from above will be higher 35 than its downward curved end to provide a continuously descending passage to the heat exchanger 12.

The box upon the outside of and enclosing the 40 evaporator pipe 4 consists of two side plates 1 having turned flanges 1c at one end to form a back, and having outwardly extending flanges 1a at the front, which sides and back are adapted to lie closely adjacent the outside walls of the pipe sections 4. Flanges 1b are also provided on the upper edges of the side plates 1 adapted to be accommodated in the downwardly and inwardly turned edges 9a of top 9 and make a tight sliding fit therewith. The two pieces of sheet metal 50 1 forming the sides and back of the box are se-

cured closely adjacent pipe sections 4 by a series of half-sleeves 2, affixed by their flanges 3 to sides 1. These half-sleeves have integral channelled fins 5 projecting into the box. The said fins 5 of the various half-sleeves are at different positions upon the sleeves, some being higher than others to compensate for the difference in level of the two sides of the pipe sections, so that when shelves 6 are mounted with their opposite edges in channels formed in fins 5 they will be horizontal. These shelves have vertical rear portions 6a recessed at 6b, and chamfered at 6c, the recesses 6b being to avoid the fins 5 on which the shelf is carried and the chamfers 6c to avoid the half-sleeves 2 carrying the next highest shelf while being moved rearwardly in the channels. Each upturned portion 6a forms a part of the inner rear wall of the box. Sheet metal liners 7 (see Figures 8 and 9) are moved rearwardly until their rear ends are between the side edges of the upturned ends 6a of shelves 6 and half-sleeves 2 and form the sides of compartments between the shelves 6. When the shelves 6 and liners 7 have been located, right angled cover plates 8 are mounted over the forward ends of the liners 7 and secured by studs 8a to the flanges 1a of the sides 1 (see Figure 3). A flanged face plate 10a to which door 10 is also hinged is secured by studs 8a around the open framework of the box as shown in Figures 1 and 2. A modified form of half-sleeve formed of sheet metal is shown in Fig. 15, parts similar to the parts of half-sleeve 2, being designated by the same reference numerals with subscripts.

In a further modification shown in Fig. 15, the fins 5a of half-sleeve 2a may be thin and unchannelled in which case the shelves 6a could be provided with a channelled edge 6b to enable them to slide along fins 5. In lieu of the separate liners 7 upturned side edges of the shelves 6 could be adapted to form the sides of the inner wall of the chambers. Furthermore the half-sleeves 2 could be finless and provided with a longitudinal channel along which the edges of the shelves 6 could slide and be held.

I claim:

1. In a refrigerator of the absorption type, having an evaporating coil in the form of a plurality of substantially horizontally disposed U-shaped turns, said turns being arranged in superimposed vertically spaced relation with corresponding portions of the several turns in vertical alignment, a low temperature cooling chamber consisting of thin metal outer sides having front flanges and back held to the turns of the evaporator coil by flanged half-sleeves passing around said turns; longitudinal channelled fins upon said half-sleeves; shelves with upturned rear ends for forming sections of the rear inner wall, the side edges of said shelves being slidable in the channels of the fins, and provided with chamfers and slots for avoidance of obstacles; liners for location between the upturned ends of said shelves and the half-sleeves on the one hand, and behind right angled cover plates secured to the front flanges on the outer sides on the other hand; flanges on the tops of said sides, a top with inturned side edges for sliding along the flanges on the tops of said sides; a face plate secured upon said cover plates, and a door hinged to said face plate.

2. In a refrigerator of the absorption type having an evaporating coil in the form of a plurality of substantially horizontally disposed U-shaped turns, said turns being arranged in superimposed vertically spaced relation with corresponding portions of the several turns in vertical alignment, a low temperature cooling chamber consisting of thin metal outer sides and back positioned about said coil, U-shaped half sleeves surrounding opposite legs of the coil turns and secured to said sides, fins on said sleeves extending inwardly between the opposite legs of the coil turns, and shelves slidably mounted upon said fins.

3. In a refrigerator of the absorption type having an evaporating coil in the form of a plurality of substantially horizontally disposed U-shaped turns, said turns being arranged in superimposed vertically spaced relation with corresponding portions of the several turns in vertical alignment, a low temperature cooling chamber consisting of thin metal outer sides and back positioned about said coil, U-shaped half sleeves surrounding opposite legs of the coil turns and secured to said sides, channelled fins on said sleeves extending inwardly between the opposite legs of the coil turns, and shelves slidably mounted in said channels.

4. In a refrigerator of the absorption type having an evaporating coil in the form of a plurality of substantially horizontally disposed U-shaped turns, said turns being arranged in superimposed vertically spaced relation with corresponding portions of the several turns in vertical alignment, a low temperature cooling chamber consisting of thin metal outer sides and back positioned about said coil, U-shaped half sleeves surrounding opposite legs of the coil turns and secured to said sides, said sleeves having channels formed therein and disposed on the inner sides of opposite legs of the coil turns, and shelves slidably mounted in said channels.

5. In a refrigerator of the absorption type having an evaporating coil in the form of a plurality of substantially horizontally disposed U-shaped turns, said turns being arranged in superimposed vertically spaced relation with corresponding portions of the several turns in vertical alignment, a low temperature cooling chamber consisting of thin metal outer sides and back positioned about said coil, U-shaped half sleeves surrounding opposite legs of the coil turns and secured to said sides, fins on said sleeves extending inwardly between the opposite legs of the coil turns, and shelves slidably mounted upon said fins and having channels to receive said fins.

6. In a refrigerator of the absorption type having an evaporating coil in the form of a plurality of substantially horizontally disposed U-shaped turns, said turns being arranged in superimposed vertically spaced relation with corresponding portions of the several turns in vertical alignment, a low temperature cooling chamber consisting of thin metal outer sides and back positioned about said coil, U-shaped half sleeves surrounding opposite legs of the coil turns and secured to said sides, fins on said sleeves extending inwardly between the opposite legs of the coil turns, and shelves slidably mounted upon said fins and having upturned rear portions.

GEORGE RAYMOND GOLDSMITH.
